UNITED STATES PATENT OFFICE.

CHARLES L. BUCKINGHAM, OF NEW YORK, N. Y.

ELECTRIC-ARC LAMP.

SPECIFICATION forming part of Letters Patent No. 320,843, dated June 23, 1885.

Application filed January 14, 1885. (No model.)

To all whom it may concern:

Be it known that I, CHARLES L. BUCKINGHAM, of the city, county, and State of New York, a citizen of the United States of America, have made a new and useful Improvement 5 in Electric-Arc Lamps, of which the following is a specification.

My invention consists in the arrangement of suitable mechanism with a clutch adapted to 10 separate the carbons of an electric lamp and to establish the arc; to next unclamp the carbon-holder, leaving said carbon-holder suspended by a train of wheels, and to then return to its normal position and remain in readiness 15 to re-establish the arc to its normal length in case of over-feeding upon the release of the gear-train. To this end, preferably, an arc branch electro-magnet is employed to raise the 20 clutch, while a shunt electro-magnet next operates to short-circuit the arc branch electro-magnet upon the establishing of a normal arc, thereby permitting the clutch to return to its normal position, and a second shunt-magnet serves to release the wheel-train which 25 supports the carbon-holder upon an abnormal increase of arc-resistance.

p is an arc branch electro-magnet, having a hollow axial armature, *q*, through which passes a cylindrical carbon-carrier, *R*. The axial armature *q* is provided with a lifting-toe, which 30 serves to lift a clamping-ring, *s*, of a well-known form, thus lifting the carbon-holder upward until the opposite side of the tilted clamping-ring is raised against a limiting-stop, *r*. *h* is a portion of the lamp-frame, upon 35 which is supported a train of wheels, *b b' c d e f g*. The carbon-holder is provided with a longitudinal groove having rack-teeth whose crowns or points are flush with the cylindrical 40 surface of said holder. By thus arranging the rack-teeth of the carbon-holder its surface is rendered suitable for use with the ring-clutch. The pinion *b* gears into the rack of the carbon-holder and is rigidly fixed upon the same ar- 45 bor to a ratchet-wheel, *b'*. The wheel *c* is pro- 50 vided with a pawl, *d'*, which takes into the teeth of wheel *b'*, thereby communicating the downward force of the upper carbon, *c*, and the carbon-holder *R* to the gear-train. When, 55 however, the carbon-holder is raised upward by the clamping-ring, the ratchet-teeth of wheel *b'* slide backward under the free end of

point *d'* without rotating other portions of the gear train than pinion *b* and wheel *b'*. Wheel *g* is the last wheel of the train, and is prefera- 55 bly a rotating escapement-fly adapted to regulate the motion of the train. Armature *j* of shunt electro-magnet *k* is adapted to arrest the rotation of the fly-wheel *g* when in its back position, but to release said train when at- 60 tracted by the shunt electro-magnet. *l* is an electro-magnet, also placed in the shunt branch, which attracts its axial armature at the moment a normal arc is established, or much before *k* attracts armature *j*. It will now be seen that 65 if carbon points *c c'* are together, a current, when first passed over the line, will cause the carbon-holder to be raised through the agency of arc branch electro-magnet *p*. Armature *j* will at the same time hold the feed-train locked. 70 When a normal arc is established, electro-magnet *p* is short-circuited through contact *m* and armature *n*, enough current having then been diverted through the shunt branch to cause electro-magnet *l* to attract its armature to the 75 front position. When short-circuited, electro-magnet *p* loses its magnetism, and clamp *s* drops to its lowest position, and the carbon-holder is again free to slide through its cylindrical open- 80 ing; but when the carbon-holder is released by the lifting-clamp it is sustained by the feeding-train which still remains locked by armature *j*, and is only released when the carbon points have so far burned apart as to cause an abnor- 85 mal arc-resistance. The armature *n* of electro-magnet *l* should be so adjusted that it will be promptly retracted upon a decrease of arc-res- 90istance but little below the normal, thus caus- ing the arc current to flow through *p*, and again lift clutch *s* to re-establish the arc to its nor- mal length.

Instead of a gear-train and a shunt-branch electro-magnet to effect feeding, a shunt-branch electro-magnet may be employed to release any well-known clamping device commonly 95 used to suspend the carbon-holder and to feed the same as the carbons are consumed without departing from my invention. All that is necessary of a clamping device is that it shall admit of the raising of the carbon to establish 100 an arc, to then hold the carbon suspended, and to permit the downward feed of the carbon under the action of gravity upon the occurrence of an arc of abnormal resistance.

What I claim, and desire to secure by Letters Patent, is—

1. In an electric lamp, the combination of a lifting-clutch, an arc-branch electro-magnet for raising said clutch, a shunt-branch electro-magnet for causing the clutch to release the carbon-holder and return to its normal position, and a feeding device controlled by a shunt-branch electro-magnet, which permits the carbon-holder to feed under the action of gravity. 30
  2. The combination of an arc-branch electro-magnet, a lifting-clutch which is first actuated by said arc-branch electro-magnet, a carbon-holder provided with rack-teeth which is lifted by said clutch, a shunt-branch electro-magnet to control the release of said clutch from the carbon-holder and its return to its original position, a train of wheels which is normally locked for holding the carbon-holder suspended when it is released from the lifting-clutch, and a shunt-branch electro-magnet for releasing said train of wheels to permit the carbons to feed. 35
  - 25 3. The combination of a carbon-holder, a lifting-clutch, an arc-branch electro-magnet adapted to raise said clutch, and a shunt-branch electro-magnet for controlling its release and return to its original position, a gear-train for 40
- controlling the feed movement of said carbon-holder, and a shunt-branch electro-magnet for releasing said train. 45
4. The combination of a gear-train whose last wheel has a free backward movement, a carbon-holder having rack-teeth with which said wheel gears, and which is suspended against the action of gravity by said train, a shunt-branch electro-magnet, an escapement-wheel controlled by said electro-magnet for releasing said train, a lifting-clutch adapted to raise the carbon-holder, and an electro-magnet for controlling the release and return of said clutch to its original position. 50
  5. The combination of a suspending and feeding train of wheels, a shunt-branch electro-magnet for controlling said train, a carbon-holder, a clutch adapted to raise and release said carbon-holder and to return to its original position in readiness to re-establish the arc in case of over feeding, an arc-branch electro-magnet to control said clutch, and a second shunt-branch electro-magnet adapted to short-circuit the arc-branch magnet upon the forming of a normal length of arc. 55
